UNITED STATES PATENT OFFICE

ALEXANDER BOYNTON, OF SAN ANTONIO, TEXAS

STAGE LIFT FLOWING DEVICE

Application filed November 4, 1927. Serial No. 231,073.

My invention relates to automatic stage lift flowing devices such as disclosed in my co-pending applications Serial Nos. 181,144, filed April 5, 1927 and 192,049, filed August 5 24, 1927, and more particularly to an improved valve for controlling the admission of the lifting agent to the fluid elevating conduit at various stages or elevations.

In the embodiment of the inventions disclosed in these applications, valves of the thrust or longitudinally movable type are employed for automatically controlling the passage of the lifting agent to the liquid elevating conduit. The present invention contemplates an automatic valve wherein the valve element is movable at right angles to the direction of flow to open and closed positions thereby reducing impact or shock to the contacting parts to a minimum.

Further the invention provides a valve for well flowing devices which is smooth in operation and capable of delicate and sensitive adjustment.

The invention also provides a valve of this type wherein the valve element is arranged to roll upon and away from the valve seat thus freeing the latter at all times of paraffin, asphalt or other gummy substances which are elevated from oil wells incident to flowing 20 of the latter.

With the preceding and other objects and advantages in mind, the invention consists in the novel combination of elements, constructions and arrangement of parts to be hereinafter specifically referred to, claimed and illustrated in the accompanying drawing, wherein:

Figure 1 is a longitudinal sectional view of my improvement;

Figure 2 is a similar view of a modification of the invention; and

Figure 3 is a detail view of the adjustable follower used in connection with other embodiments of the invention.

Referring to the invention in detail and more particularly to Figure 1 wherein a tubing adaptation, referred to in connection with the co-pending application Serial No. 181,144, a cylindrical conduit threaded at its opposite ends for engagement with the adja-

cent tubing sections, not shown, is provided. A relatively small bore longitudinally extending circular chamber or fluid passage-way 6 is formed with one side of the conduit 5 and extends the entire length thereof. The 55 lower end of the chamber 6 is open to communicate with the well casing not shown, while communication between the conduit 5 and chamber is established by way of a port 7 extending transversely through one side of the conduit and chamber adjacent to its lower end, the port opening into a concave valve seat 8 upon the interior of this chamber 6. In drilling or otherwise forming the transverse port 7 and valve seat it is necessary to 65 provide an opening in the chamber 6 at a point diametrically opposite this port, and, after the drilling operation, the opening is sealed by a threaded plug 4. A vertically and laterally movable spherical valve element 9, adapted to seat upon the seat 8 to sever communication between the conduit and the well casing when the external or casing pressure exceeds the tubing pressure, is loosely mounted in the chamber. 75

To support the valve element at a point just below the valve seat when the tubing back pressure, namely, the weight of the liquid being elevated plus the lifting agent above the valve element, and plus frictional 80 resistance exceeds the external or well casing pressure, a vertically movable cylindrical plunger 10 of considerably less diameter than the bore of the chamber 6 is arranged in the lower end of the chamber and has a flat upper 85 end 11 upon which the valve element reposes for rolling movement thereon.

When the valve is in open position the plunger 10 rests directly upon a tubular bushing 12 threadedly engaged with the lower end 90 of the chamber. In order to centralize the plunger while resting on the bushing, the upper end of the latter is formed with a central concave seat 13 while the lower end of the plunger is convex or rounded as at 14 to fit within the seat.

Cooperating with the plunger and circular valve element in permitting the valve element to remain open until a predetermined differential pressure exists between the tub. 100

ing pressure and the casing pressure is an expandible coil spring 15 which is arranged in the upper end of the chamber and rests upon a cylindrical follower 16 loosely fitted within the chamber and terminates at its lower end in a stem 17 of relatively small diameter. For example, if the plunger 10 and follower 16 are each $\frac{1}{2}$ " in diameter, the stem would be $\frac{1}{16}$ " in diameter, and for this size of plunger and follower the chamber 6 would be $\frac{5}{8}$ " in diameter. The difference in diameter between the plunger 16 and plunger chamber 6 should vary between .005" and .025". The diameter of ball 9 should be approximately the same diameter as the plunger 16, but may be as much as $\frac{1}{16}$ " less than the diameter of the plunger. The length of coil spring 15 should vary from 4" to 6". The diameter of the spring wire of the grade of music wire should be between .110" and .125" on pitches which may vary from four to six coils to the inch. All other dimensions may be substantially as shown.

The devices should be so spaced in the tubing string that the weight of fluid in the tubing between adjacent devices is from one-fourth to one-half as much as the pressure per square inch required to compress the spring and thereby force the plunger to sealing-off engagement upon its upper seat. For illustration, assume the weight of the fluid between any two adjacent devices to be 30 lbs. per square inch, then the pressure per square inch required to compress the spring and seal-off the plunger upon its upper seat should be 60 lbs. to 120 lbs.

The above spacing gives the best results and states the spacing rule correctly, but flow will be initiated and maintained if the weight of the fluid per square inch between the valves is only slightly less than the pressure per square inch required to compress the spring sufficiently to cause the plunger to seal-off upon its upper seat. For illustration, assume the weight of the fluid between any two adjacent devices to be 30 lbs. per square inch, then the pressure per square inch required to compress the spring until the plunger seals-off upon its upper seat must be slightly over 30 lbs. and should, as first stated, be from 60 lbs. to 120 lbs. The lower end of this stem rests upon the circular valve element and in order to reduce the friction between this valve element and stem its contacting end 18 is flat so that it will have but a slight bearing surface on the valve element.

At its upper end the expandible spring is normally spaced from the upper or end wall of the chamber so that the plunger, valve element and follower will move a predetermined distance before the spring will abut this end wall and place the spring under compression. This condition is necessary in order to permit the plunger and valve element to rise sufficiently to permit the casing

pressure to pass through the chamber and build up with the tubing. It will be observed that as the pressure builds up in the tubing the valve element is slowly seating to throttle down the casing pressure as the tubing pressure approaches the pressure necessary to lift a predetermined weight or volume of liquid a predetermined elevation, at a predetermined velocity.

Operation

70

75

The casing pressure lifts and sustains the plunger, valve element, follower and spring, permitting pressure fluid to pass into the conduit and well tubing connected therewith. As the upward moving column of liquid in the tubing attains maximum velocity, the tubing pressure decreases, establishing a pressure differential between the external or casing pressure and the tubing pressure. That is, the casing pressure now exceeds the weight of the liquid column plus tubing pressure, which of course includes frictional resistance due to velocity. The differential pressure now existing further lifts the plunger with sufficient force to engage the expandible spring with the end wall of the chamber, placing the latter under compression. The expandible spring being of a given potential strength has to be compressed a predetermined degree by a predetermined force (the casing pressure) to permit the plunger to be elevated to such height as to dispose the valve element in horizontal alignment with the valve seat 8. Pressure rushing through the port 7 into the conduit draws the spherical valve element against the seat gradually throttling the pressure supply and finally sealing the port.

It follows that no further casing pressure can enter the tubing until the tubing pressure approaches the casing pressure to a degree where the potential energy of the compressed spring and weight of the follower will disengage the valve element from its seat, permitting the latter to roll laterally away from the seat gradually increasing the intake area to the transverse port.

Due to the rolling engagement of the valve element with its seat, the former is at all times free to break the seal of gummy substances such as paraffin, asphalt, etc., which might be presented. In other words, these gummy substances resist the opening action of the valve in two ways—first, by adhesion, and second, by suction, or the tendency to create a vacuum between the valve seat and the valve as the latter opens. With the valve element receding directly away from the seat, it must resist and overcome both the force of adhesion and suction which is acting upon the entire area of the opposed faces of the valve seat and valve element. It will be observed that my invention overcomes these objections in that the vacuum is first broken

80

115

120

upon one side of the valve and its seat and thereby completely destroys the vacuum. Similarly, the adhesion of the gummy substances is overcome at one point upon the seat and valve and permits the latter to pull 5 away from the seat.

In Figure 2 a modification embodying what is referred to in the co-pending application Serial No. 181,144 as the casing adaptation, is disclosed. In this embodiment of the invention the chamber 6 receives a threaded plug 20 in one side at a point intermediate its ends, having a central outlet 10 21 and a concave valve seat 22 upon its inner face while communication between the conduit and the chamber is established by way of a transverse port 23, the latter being disposed below the plug 20. With this construction the operation of the valve is the same except fluid pressure is conducted 15 through the conduit and associated well tubing, and the liquid raised or elevated in the well casing.

In Figure 3 a modification of the follower 20 is illustrated wherein the stem 17 has a threaded end 24 adjustably received in a threaded bore 25 in one end of the follower whereby the stem may be lengthened or shortened to increase or decrease the tension 25 of the expansible coil spring. However, in lieu of this adjustable follower thin washers or shims may be interposed between one end of the spring and end wall of the chamber, or the opposite end of the spring and the follower disclosed in Figure 1. Moreover, an expansible spring of greater strength than the one herein disclosed may be employed 30 in lieu of this adjustable follower.

40 What is claimed is:

1. A valve comprising a body having a chamber and an outlet port for the passage of fluid, a plane-ended plunger movable in the chamber by fluid flowing toward the port 45 and a valve element adjacent to said end of the plunger, being capable of rolling upon that end into sealing-off engagement with the port when in proximity thereto.

2. A valve comprising a body having a chamber and an outlet port for the passage of fluid, a plunger located in the chamber being movable in the direction of the port under the influence of flowing fluid and being level at that end nearest the port, and a ball 55 in advance of the plunger, rolling upon said end into sealing-off engagement with the port when in proximity thereto.

3. A valve comprising a body having a chamber and an outlet port for the passage of fluid, a plunger located in the chamber being movable in the direction of the port under the influence of flowing fluid and being level at that end nearest the port, a ball in advance of the plunger, rolling upon said end into sealing-off engagement with the port when in proximity thereto, and means re-

sisting the movement of both the plunger and ball.

4. A valve comprising a body having a chamber and an outlet port for the passage of fluid, a ball located in the chamber, and a pair of plungers between which the ball is situated, the assembly being shifted in one direction under the pressure of fluid until the ball confronts the port with which it is drawn into sealing-off engagement from between the plungers. 75

5. A valve comprising a body having a chamber and an outlet port for the passage of fluid, a ball located in the chamber, a pair of plungers between which the ball is situated, the assembly being shifted in one direction under the pressure of fluid until the ball confronts the port with which it is drawn into sealing-off engagement from between the plungers, and a spring associated with one of the plungers to resist the shifting of said assembly and returning the assembly to a former position upon cessation of the fluid pressure. 80

6. A valve comprising a body having a chamber and an outlet port for the passage of fluid, a ball located in the chamber, and a pair of plungers having confronting ends of different areas with which the ball contacts and in respect to which the ball rolls to a sealing-off position under sufficient fluid pressure when confronting the port. 85

7. A valve comprising a body having a chamber and an outlet port for the passage of fluid, a ball located in the chamber, a plunger having a level end upon which the ball rests and rolls into sealing-off engagement with the port when in confronting position and under sufficient fluid pressure, and a follower having a stem contacting the ball, the point of contact being of less area than the end of the plunger to avoid impedance of the action of the ball. 100

8. A valve comprising a body having a chamber and an outlet port for the passage of fluid, a plurality of plungers loose in the chamber and subject to opposite axial movements under opposed forces, and a valve element held between adjoining plungers but being otherwise loose in the chamber, said element being movable with the plungers but also capable of digression from axial movement to assume a sealing-off engagement with the port. 110

9. A valve comprising a body having a chamber with fluid inlet and outlet ports, and a ball and plunger in movable engagement with each other and adapted to move together axially of the chamber and temporarily remain suspended under increasing or diminishing pressures of fluid flowing through the chamber between the ports, the ball being adapted to roll laterally by fluid pressure to a sealing-off position when adjacent to one of the ports. 115 120 125 130

10. A valve comprising a body having a fluid passageway with inlet and outlet ports affording communication between the interior and exterior of the body, a pair of separate valves both movable axially of the passageway by force of fluid flowing through the passageway, one laterally departing from the other to seal off one of the ports under a sufficiently high fluid pressure.

11. A valve comprising a chamber having fluid inlet and outlet ports, a support disposed at one side of said outlet port, a ball normally resting on the support out of line with the outlet port, and means tending to seat the support on the inlet port and to resist movement of the support and ball toward the outlet port.
